UNITED STATES PATENT OFFICE.

SAMUEL T. WHITE, OF DAVENPORT, IOWA.

DOLLY-SUPPORT FOR WASHING-MACHINES.

1,160,555.

Specification of Letters Patent. Patented Nov. 16, 1915.

Application filed February 10, 1915. Serial No. 7,304.

To all whom it may concern:

Be it known that I, SAMUEL T. WHITE, a citizen of the United States, residing at Davenport, in the county of Scott and State of Iowa, have invented new and useful Improvements in Dolly-Supports for Washing-Machines, of which the following is a full, clear, and exact description.

My invention relates to improvements in washing machines, and more particularly to the dolly supporting devices for the type of machine designed for and used in ordinary households.

The objects of my invention are to provide means by which the dolly sleeve may be easily removed for cleansing purposes; to so construct the sleeve that it will extend to the bottom of the machine tub, and to so shape, arrange and support the lower end of said sleeve that any tendency to tear or rip clothes during the washing operation is avoided. These objects I accomplish by the means hereinafter fully described, and as particularly pointed out in the claims, reference being had to the accompanying drawings forming a part hereof, in which—

Figure 1 is a vertical central section of my improved washing machine, the lower portion of the supporting legs being broken away. Fig. 2 is an enlarged fragmentary central vertical section through the lower portion of the dolly sleeve and the shaft casing, and exposes the rotary reciprocable shaft. Fig. 3 is an enlarged transverse horizontal section on line 3—3, Fig. 2, looking upward. Fig. 4 is an enlarged fragmentary central section through the top portion of the sleeve and the shaft casing, showing a top fragment of the rotary reciprocable shaft. Fig. 5 is a top plan of the sleeve, the rotary reciprocable shaft and the casing for said shaft.

Referring to the drawings, A represents the tub of a washing machine of well-known construction, which is provided with a top cover B suitably connected thereto by hinges, and is mounted upon and supported by legs a so that its bottom b is a suitable distance above the ground.

A hanger or bracket depends from the bottom b of the tub and slidably supports a rack 2, which is reciprocated in any suitable manner and meshes with a pinion 3 mounted on a vertical rotary reciprocable shaft 4. The hanger has an enlarged top attachment-plate 5 which is secured to and strengthens

the bottom b of the tub, and this attachment-plate 5 is provided at its center with a depending boss 6. The lower portion of the hanger or bracket is provided with a lateral extension 7 that has suitable bearings for the lower end of a vertically disposed rotary reciprocable shaft 4.

A vertical tubular casing 8 forms a housing in which the rotary reciprocable shaft 4 is loosely inclosed, and the lower end thereof is, preferably, exteriorly screw-threaded, as shown at 9 in Fig. 2, and extends through the bottom of the tub and into and through boss 6 of the hanger attachment-plate. The upper end of shaft 4 projects above the upper end of casing 8 and is, preferably, separated at this point from said casing by an interposed annular bushing 10 that centers and also journals the shaft in 75 the casing.

To the upper projecting end of shaft 4 I prefer to fasten a top-block, which, in the adaptation of my invention shown in Figs. 4 and 5 of the accompanying drawings, has 80 a substantially square head 12, and a lower circular flange 13 which fits and rests upon the top edge of the casing. This top-block has a suitable recess 14 in which the shaft end is, preferably, permanently and rigidly 85 fastened by a rivet 15. I mount a dolly sleeve 16 upon and support it from the upper end of shaft 4 in such manner that it can be easily and quickly detached from or attached to the same in order to permit its 90 convenient removal and replacement for cleaning or repairing, and, preferably, by providing the top 17 of the dolly sleeve 16 with an aperture of substantially square outline in which the head 12 of the top-block 95 fits and is removably fastened by inserting a cotter pin 18 in an opening in the head above the upper edge of the dolly sleeve, as shown in Fig. 4.

The dolly sleeve 16 is constructed sufficiently long to extend, when properly attached to and suspended from the top of shaft 4, to or nearly to the bottom of the tub. The lower extremity of this sleeve is, preferably, provided with a peripheral enlargement or flange 19, and its bore is slightly reduced to provide a fairly close fitting bearing between it and the casing at this point, as shown at 20 in Fig. 2. To confine the lower extremity of the dolly sleeve, 110 a cone-shaped arbor or block 21 is securely mounted upon the lower portion of casing 8

that rests upon the bottom of the tub, and a concentric cup-like concavity 24 of considerably larger size than its central opening 22, the circular side-wall 23 of which 5 curves outwardly and upwardly and forms a bearing in which the peripheral flanged lower end of the dolly sleeve journals.

The bottom 25 of the cup-like concavity of block 21, preferably, has a slight downward slant from the casing to its juncture 10 with the circular side wall 23 thereof, and drains the soiled and dirty water that may pass into the cup from openings 26, that extend from the juncture of the side and bottom walls (the lowest part of the cup) and 15 extend downward and outward, as shown in Fig. 2.

For lightness of construction the under-side of block 21 is cored out to produce opposed segmental recesses 27 which are separated by solid radial walls 28 of metal in which drain openings 26 are located, as shown in dotted lines in Fig. 3. If desired, the concavity of block 21 may be partially 25 fitted with Babbitt or other suitable anti-friction metal, and thus form a practical journal for the lower end of the sleeve.

The dolly sleeve is, preferably, constructed with oppositely arranged longitudinal 30 ribs or tenons 29 and a dolly or agitator removably mounted thereon, which has a disk like body 30 in the center of which an opening is made having diametrically opposite 35 grooves (not shown) into which, when the dolly is mounted on said sleeve, its ribs or tenons will enter, thereby permitting longitudinal sliding movement of the dolly upon the dolly sleeve, while preventing independent rotation of the same. The dolly has the 40 usual pegs 31 projecting downward therefrom, and in order to maintain it in a proper elevated position within the tub, I prefer to terminate the ribs or tenons of the sleeve at a suitable distance above the bottom of the 45 tub and provide a peripheral flange 32 at or in the vicinity of such terminal points upon which the body of the dolly or agitator rests.

The operation of my invention is substantially as follows; to-wit: The rack 2 being reciprocated its movement is imparted to pinion 3, which in turn gives a rotary reciprocal motion to the vertical shaft 4. This shaft 4, through the medium of the 55 top-block imparts its rotary reciprocal motion to the dolly-sleeve 16 and correspondingly rotates the dolly or agitator, thereby stirring the clothes immersed in the washing water in the tub. As the dolly revolves 60 in unison with the dolly-sleeve and said sleeve extends continuously down from above the upper end of the casing to or near the bottom of the tub, and as the lower end of said dolly-sleeve extends within and is 65 journaled in a top cup-like opening in the

cone-shaped block on the bottom of the tub and the top of said block projects above the lower end of the sleeve, it is practically impossible to rip or tear the clothes during the washing operation. The clothes, during the 70 washing operation, creep up the outer cone-shaped sides of the block, and over the very slight space between the circumference of the flanged lower end of the sleeve and the edge of the concavity of said block and move 75 with the sleeve. As the clothes in the tub can only tear when one part thereof is held stationary while another part is moved, and as, in my improved construction, this is impossible, my improvements avoid the tearing 80 of the clothes around the lower end of the tubular post of casing, which heretofore very frequently happened.

What I claim as new is:—

1. In a machine of the class described, a 85 tub, a vertical tubular casing mounted in stationary position within the tub and having its lower end extending through the bottom of the tub, a vertical rotary shaft extending through the casing, a cone-shaped 90 block secured to the tub bottom and surrounding the casing, said block having a top cup-like concavity, the circular surrounding wall of which curves upwardly and outwardly at a slight angle to the perpendicular, a dolly-sleeve mounted on the upper end of the rotary shaft and surrounding 95 and concentric with the casing and having its lower extremity provided with a peripheral flange which fits and seats within 100 the concavity of the block.

2. In a machine of the class described, a 105 tub, a vertical tubular casing mounted in stationary position within the tub and having its lower end extending through the bottom thereof, a vertical rotary shaft journaled in suitable bearings beneath said tub and extending through the casing, a cone-shaped block secured to the bottom of the tub and surrounding the casing and having a cup-like concavity in its upper portion, a dolly sleeve mounted on the upper projecting end of the rotary shaft and depending 110 therefrom around and concentric to said casing and having its lower extremity seated in the cup-like portion of the cone-shaped block.

3. In a machine of the class described, a 120 tub, a vertical tubular casing mounted in stationary position within the tub and having its lower end extending through the bottom thereof, a vertical rotary shaft journaled in suitable bearings beneath said tub and extending through the casing, a cone-shaped block secured to the bottom of the tub and surrounding the casing and having a cup-like concavity in its upper portion provided with an annular nearly vertical side wall, a dolly sleeve mounted on the upper projecting end of the rotary shaft and 125 130

depending therefrom around and concentric to said casing and having its lower extremity seated in said cup-like concavity of the cone-shaped block with the peripheral 5 margin of said extremity in contact with the outer side-wall of the cup-like concavity of the block.

4. In a machine of the class described, a tub, a vertical tubular casing mounted in 10 stationary position within the tub and having its lower end extending through the bottom thereof, a vertical rotary shaft journaled in suitable bearings beneath said tub and extending through the casing of a cone- 15 shaped block secured to the bottom of the tub and surrounding the casing and having a cup-like concavity in its upper portion the outer side-wall of which is circular and nearly vertical and the bottom of which extends inwardly and upwardly, and said 20 block being provided with drain openings extending outwardly from the juncture of said side and bottom of its concavity, a dolly sleeve mounted on the upper project- 25 ing end of the rotary shaft and depending therefrom around and concentric to said casing and having its lower extremity seated in the cup-like concavity of said block.

5. In a machine of the class described, the 30 combination with a tub, a vertical casing in said tub, a rotary shaft housed in and extending through said casing, a cone-shaped

block fitted around the lower portion of said casing and upon the bottom of the tub and having a cup-like concavity in its top 35 portion, and an agitator or dolly having a comparatively long sleeve having its upper end removably mounted upon the upper end of the shaft and its lower end seated in the cup-like top portion of said block; said 40 sleeve being concentric with and surrounding the casing throughout.

6. In a machine of the class described, the combination with a tub, a vertical casing in 45 said tub, a rotary shaft housed in and extending through said casing, a cone-shaped block fitted around the lower portion of said casing and upon the bottom of the tub and having a cup-like concavity in its top portion, and an agitator or dolly having a com- 50 paratively long sleeve having its upper end removably mounted on the shaft and having a peripherally flanged lower end seated in the cup-like concavity of its top portion, said sleeve being concentric with and sur- 55 rounding the casing throughout.

In witness whereof, I have hereunto set my hand and seal this 30th day of January, 1915.

SAMUEL T. WHITE.
